OPHTHALMIC SLIT LAMP

David E. Staub, Clearwater, Fla., assignor to
Concept, Inc., St. Petersburg, Fla.

Filed Mar. 31, 1971, Ser. No. 130,047

Term of patent 14 years

Int. Cl. D24—02

U.S. Cl. D57—1 E

FIG. 1

FIG. 2

FIG. 3

FIG. 4

FIG. 1 is a side elevation of the ophthalmic slit lamp.
FIG. 2 is a view similar to that shown in FIG. 1 except
that the same has been rotated through an arc of 45°.

FIG. 3 is an end view of the design described in FIGS.
1 and 2 looking from left to right in FIG. 2.

FIG. 4 is an end view of the design looking in the direc-
tion of right to left of FIG. 2.

I claim:

The ornamental design for an ophthalmic slit lamp, as
shown.
